United States Patent Office.

CHARLES B. LOVELESS, OF SYRACUSE, NEW YORK.

Letters Patent No. 98,174, dated December 21, 1869.

GAS-GENERATOR AND BURNER.

The Schedule referred to in these Letters Patent and making part of the same.

To all whom it may concern:

Be it known that I, CHARLES B. LOVELESS, of Syracuse, in the county of Onondaga, and in the State of New York, have invented new and useful Improvements in Gas-Generators and Burners; and I do hereby declare that the following is a full, clear, and exact description thereof, reference being had to the accompanying drawings, and to the letters of reference marked thereon, in which—

Figure 1 is a vertical section through the centre of the invention and supply-tube.

Figure 2 is a plan view of the cylinder, filled with holes, at which point the gas is burned, also showing the tubes conveying the gas to the burner, from the generator.

The nature of my invention consists in the use of double pipes and generator, to convey the oil to the generator, where it is converted into gas, and conveying the gas to the burner, all of which will be herein-after more fully explained.

To enable others skilled in the art to make and use my invention, I will proceed to describe its construction and operation.

In the construction of my invention, in fig. 1, A is the supply-pipe, for conveying the oil from the reservoir to the generator. The red lines in said pipe indicate the packing, to assist in regulating the flow of oil.

B, the regulating-screw.

C, the joint, for connecting the pipes and the screw B.

D, the inside pipe, which conveys the oil up to the bulb or generator F, where the oil is converted into gas.

A second pipe, E, surrounds the inner pipe D, and is screwed into the bulb or reservoir F, gas-tight, and which is also at the lower end screwed into the centre of the burner, from which are hollow arms a a, joined to the cylinder or burner, through which pipe and arms the gas is conveyed from the generator to the burner, where the gas is represented as burning

in red lines in fig. 1, and letters b b, which also shows the burner hollow.

The top of the burner is perforated with holes, as seen in fig. 2, at which point the gas is burned, as seen in fig. 1.

To the lower end of the burner is attached a holder, H, to support the chimney G.

In the operation of my invention, the oil having been put into a reservoir, it is turned on by turning the cock B, when it passes up the inner pipe D to the generator F, where it is converted into gas, and descends in the outer pipe E to the open arms a a, and enters the burner b b, and is burned, as seen in red lines in fig. 1.

In first starting the gas, I have to heat the generator with a sponge, saturated with any burning-fluid, or fill the cup, at the bottom of the burner, with any burning-fluid, and set the same on fire. This will at once generate the gas, and, with the chimney on, when once started, it will continue to burn as long as desired.

By this arrangement, it will be seen that I make a very cheap and brilliant light, and one that is perfectly safe.

Having thus described the construction and operation of my invention,

What I claim as new, and desire to secure by Letters Patent, is—

The combination of the pipes D and E with generator F, supply-pipe A, and burner b b, and chimney G, substantially as described, and operating as and for the purposes set forth.

In testimony that I claim the above-described invention as an improved gas-generator and burner, I have hereunto signed my name, this day of 1869.

CHARLES B. LOVELESS.
